UNITED STATES PATENT OFFICE.

GEORGE CLARK, OF LANDSBOROUGH, VICTORIA, AUSTRALIA, ASSIGNOR TO ALFRED HENRY STANBROUGH, TRADING AS MONO SITU CONCRETE COMPANY, OF RICHMOND, AUSTRALIA.

CORE FOR USE IN MOLDING CONCRETE WALLS.

1,077,952.

Specification of Letters Patent.

Patented Nov. 4, 1913.

Application filed October 15, 1910. Serial No. 587,254.

To all whom it may concern:

Be it known that I, GEORGE CLARK, a subject of the King of Great Britain, formerly residing at Gordon street, Elsternwick, but now residing at Landsborough, in the State of Victoria, Australia, architect, have invented a Core for Use in Molding Concrete Walls, of which the following is a specification.

10 This invention relates to improvements in cores for use in molding concrete walls and it proposes a core of collapsible nature which may be readily set up or collapsed and associated with or removed from the 15 molding apparatus.

The invention is illustrated by the accompanying drawings whereof:

Figure 1 is a view showing in side elevation and longitudinal section a preferred 20 form of the improved collapsible core. Fig. 2 is a transverse sectional view of the mold and the core. Fig. 3 is a plan view of the complete mold as shown in Fig. 1. In this 25 figure one of the cores is shown in horizontal section. Fig. 4 is a horizontal sectional view (viewed upward) of the core expanded in which the dotted lines indicate the position of the links thereof when the lower end of the core is contracted.

30 The molding apparatus shown comprises mold planks C, C, adapted to be set on edge face to face at the required distance apart. These planks are provided near their lower edges and on their inner or adjacent 35 sides with laterally projecting pins C', which after the first course is molded rest on the preceding course of concrete, such as B and while temporarily supporting the planks constitute the gage for the height 40 of each course. By this means the lower portion C² of the planks below the pins C' overlap the previously molded course of concrete on the outside.

The planks are clamped to form the mold 45 by devices which include vertical ribs *a* arranged opposite each other and placed against the outside of the respective planks. Each rib of the pair extends above the top edges of the planks and is connected to the other by a compression rod *b* adjusted by means of nuts engaging the threaded ends of said rod which pass through holes in the ribs *a*. By adjusting the length of the compression rod between the ribs, the grip of the

clamping device may be regulated. A draw 55 bar *H* is passed through slots formed in the vertical ribs at about the height of the course of concrete to be molded. Said bar is connected at one end by a pin *H'* to one rib and is provided at its other end with a cam lever 60 *d* adapted to bear against a preferably flattened portion of the other rib. By operating said lever the ribs *a*, *a*, are drawn toward each other and the planks are clamped against the top of the course of concrete 65 below such as B. Hopper boards *E*, provided with notches *E'* which fit over the draw bars, are placed on the top of the planks and the concrete is filled in and tamped to the level of the planks, after which the hopper 70 boards are removed and the concrete struck or leveled with the top of the planks.

The draw bars *H* are each provided on one side with a socket *e* and on the other side with two clips or lugs *f*. The collapsible core *F* which forms the subject of the present invention comprises a beveled cap piece *h* from which depend hinged flat ribbed sides *g* extending down below and inside the top of the last course of concrete, 80 while curved corner pieces *p* provided at the junctions of the sides also depend from said cap piece. The cap piece has internally two cross ribs *h*² from which depend a pair of internal stays *i* of T-section provided at 85 the lower end with a slotted cross head *j*. A central spindle *k* provided with a handle *l* passes through the boss *h'* of the cap piece and the cross head *j* and is provided at its lower end with a circular flange *m*. Pivot- 90 ed to said flange are four arms *n'*, *n*², the latter being preferably curved, connected by links *n* to the lower ends of the corner pieces *p*, while two *n'* of said links have studs *o* engaging the slots *j'* in the cross 95 head *j* and adapted to slide along same. By turning the central spindle *k* through the medium of its handle *l*, the links are expanded as in full lines, Fig. 4, and contracted by reversing the spindle as in dotted 100 lines, thus causing the core to collapse toward the lower end into an approximately taper or wedge shape, which facilitates its withdrawal from the concrete whether in a plastic or set condition. The cap piece *h* is 105 secured in position by a lug *r* on one end which fits into the socket *e* on the draw bar of the clamping device, while on the other

end are corner lugs *s* which rest on the clips or lugs *f* of the adjacent draw bar. In using this apparatus after a certain section of one course of concrete is completed, 5 the cores, are collapsed and removed after which the clamping devices and mold planks are displaced and erected ahead for another length of work and the cores replaced on the draw bars and expanded again when the 10 process of filling and tamping is continued and so on until one complete course around the building is completed.

I claim:—

15 *in situ*, a collapsible core comprising a beveled cap piece provided with a central boss and with lugs at one end and two corners, four sides and corner pieces hinged to said cap piece, two internal stays attached to

cross ribs on the latter and provided at 20 the lower end with a slotted cross head, a central spindle extending through said boss and provided with a handle, a circular flange on the lower end of said spindle provided with four arms, studs on two of the 25 latter engaging the respective slots in the cross head, and a series of links connecting said arms with the lower ends of the corner pieces substantially as set forth and as illustrated in the drawings.

30 In testimony whereof I have hereunto set my hand in presence of two subscribing witnesses.

GEORGE CLARK.
